DESIGN FOR A WIRE CARRIER BASKET

Charles C. Powell, Massillon, Ohio, assignor to
The Massillon Wire Basket Company, Massillon,
Ohio, a corporation of Ohio

Application December 27, 1947, Serial No. 143,380

Term of patent 14 years

(Cl. D58—4)

To all whom it may concern:

Be it known that I, Charles C. Powell, a citizen of the United States, residing at Massillon, in the county of Stark and State of Ohio, have invented a new, original, and ornamental Design for a Wire Carrier Basket, of which the following is a specification, reference being had to the accompanying drawing, forming part thereof.

Fig. 2 is a side elevation of the wire carrier basket shown in Fig. 1.

I claim:

The ornamental design for a wire carrier basket, substantially as shown.

CHARLES C. POWELL.
